UNITED STATES PATENT OFFICE.

WALTER A. STATTMANN, OF WILMETTE, ILLINOIS, ASSIGNOR TO UNIVERSAL NON-REFILLABLE BOTTLE COMPANY, OF CHICAGO, ILLINOIS, A CORPORATION OF ILLINOIS.

BOTTLE.

1,099,866.

Specification of Letters Patent.

Patented June 9, 1914.

Application filed June 17, 1913. Serial No. 774,097.

To all whom it may concern:

Be it known that I, WALTER A. STATTMANN, a citizen of the United States, residing at Wilmette, in the county of Cook 5 and State of Illinois, have invented certain new and useful Improvements in Bottles; and I do hereby declare the following to be a full, clear, and exact description of the invention, such as will enable others skilled in 10 the art to which it appertains to make and use the same.

This invention has for its object to provide a novel means for holding a bottle stopper within the neck of the bottle against 15 removal therefrom, and, at the same time, effecting a fluid tight joint between the outer circumference or surface of said stopper and the inner circumferential opposing 20 wall of the bottle neck.

20 In the accompanying drawings illustrating the invention—Figure 1 is a fragmentary central longitudinal section of the neck portion of the bottle equipped with a stopper and stopper-retaining means constructed in accordance with my invention. Fig. 2 is a detail perspective view of the cap employed.

My invention is particularly intended for use in mounting the valve casings of non- 30 refillable bottle stoppers within the bottle neck in a cheap, simple and efficient manner, whereby the assembling of the bottle ready for market, after filling the same, may be readily and cheaply accomplished.

35 The present invention is not confined to the use of any particular style or type of non-refillable bottle stopper but may be adapted to many different styles thereof.

In accordance with my invention I provide 40 within the neck A of the bottle an annular shoulder B upon which the valve casing C of the stopper is adapted to rest, the latter fitting relatively loosely in the upper end of said bottle neck and being 45 preferably of a length corresponding substantially with the distance from the shoulder B to the mouth of the bottle. Contiguous to its mouth the bottle is provided externally with an annular groove D in 50 which the lower edge portion E of a sheet metal cap F is adapted to be received and engaged, said portion E being crimped or spun to project into said groove D and in close contact with the upper wall thereof by

any suitable appliances adapted to this purpose. The upper wall of the cap comprises a concave or convex portion G and a depressed, substantially flat, middle portion H, the latter being provided with a central opening of smaller diameter than the valve 60 casing C.

Disposed upon the upper end of the valve casing C and upon the surrounding edge portion or mouth of the bottle is a gasket I of cork, or other suitable material, and upon 65 which the flat portion H of the cap F is adapted to bear and by means of which it is compressed upon said stopper and upon the bottle mouth so as to effect a flat, tight joint between said stopper and the bottle 70 neck. In order to allow for slight differences in length of said valve casing C or differences in the depth of the annular shoulder B in various bottles, the said flat portion H of the cap is preferably provided 75 with a plurality of annular ribs or projections J, which are adapted to bear upon the gasket I at different points to enable the latter to be more readily compressed into such close contact with the surfaces upon 80 which it rests as to insure the formation of the fluid tight joint referred to.

The concave or convex annular portion F of the cap affords a means for yieldingly taking up differences in contraction and expansion under variations in temperature between the bottle, the stopper and said cap, whereby fracture of the bottle, due to tension or compression strains thereon, is 85 obviated.

I claim as my invention:

1. A bottle provided in its neck portion contiguous to its mouth with a shoulder and provided externally contiguous to its mouth with an annular groove, a stopper fitting 95 loosely within said mouth and resting on said shoulder, a cap having an inturned portion forming a crown provided with a central opening of less diameter than said stopper, said cap being mounted upon the mouth 100 of the bottle and having its lower edge portion projecting into and engaged with said annular groove, and a gasket of a yielding material interposed between the upper wall 105 of the cap and the opposing surfaces of the stopper and the bottle mouth for effecting a fluid tight joint between the said stopper and the bottle, said inturned portion of the

- cap joining the cap annulus with a curve, the curved portion projecting above the normal plane of the inturned portion.
2. A bottle provided in its neck portion 5 contiguous to its mouth with a shoulder and provided externally contiguous to its mouth with an annular groove, a stopper fitting loosely within said mouth and resting on said shoulder, a sheet metal cap for said 10 bottle having a central depressed flat surface in its crown and a central opening therein of less diameter than said bottle, the circumferential wall of said cap extending at its lower end into said annular groove and 15 engaging in the latter for preventing removal of said cap and said stopper, and a gasket having an external diameter greater than the stopper and having a central opening of less diameter than said stopper interposed 20 between said flat portion and the stopper and bottle neck and adapted to be maintained compressed upon the latter by said flat portion for effecting a fluid tight joint between the stopper and the bottle neck.
- 25 3. A bottle provided in its neck portion contiguous to its mouth with a shoulder and provided externally contiguous to its mouth with an annular groove, a stopper fitting

loosely within said mouth and resting on said shoulder, a sheet metal cap for said 30 bottle having a central depressed flat surface in its crown and a central opening therein of less diameter than said bottle, the circumferential wall of said cap extending at its lower end into said annular groove and 35 engaging in the latter for preventing removal of said cap and said stopper, and a gasket having an external diameter greater than the stopper and having a central opening of less diameter than said stopper interposed 40 between said flat portion and the stopper and bottle neck and adapted to be maintained compressed upon the latter by said cap, the said flat portion of the latter having a plurality of annular ribs for bearing 45 on said gasket, the latter effecting a fluid tight joint between the stopper and the bottle-neck.

In testimony whereof I have signed my name in presence of two subscribing witnesses.

WALTER A. STATTMANN.
